(57) **ABSTRACT**

A new cultivar of *Buddleja* plant named 'TOBUD072' that is characterized by short internodes, conical flower spikes with white flowers and a long flowering season.

1 Drawing Sheet

1

Botanical classification: *Buddleja davidii*.

Variety denomination: 'TOBUD072'.

BACKGROUND OF THE INVENTION

The present invention relates to a new and distinct cultivar of *Buddleja* plant botanically known as *Buddleja davidii* and hereinafter referred to by the cultivar name 'TOBUD072'.

'TOBUD072' originated from open pollination of the female or seed parent a proprietary *Buddleja davidii* identified as 'BU05017' (not patented) and an unknown male or pollen parent in 2006. The resulting seeds were subsequently planted and grown. The cultivar 'TOBUD072' was selected by the inventor in 2007 as a single plant in Harkstead, Ipswich, United Kingdom.

Asexual reproduction of the new cultivar 'TOBUD072' first occurred by terminal cuttings in 2007 in Harkstead, Ipswich, United Kingdom. Since that time, under careful observation, the unique characteristics of the new cultivar have been uniform, stable and reproduced true to type in successive generations of asexual reproduction.

SUMMARY OF THE INVENTION

The following represent the distinguishing characteristics of the new *Buddleja* cultivar 'TOBUD072'. These traits in combination distinguish 'TOBUD072' as a new and distinct cultivar apart from other existing known varieties of *Buddleja*.

1. *Buddleja* 'TOBUD072' exhibits short internodes.
2. *Buddleja* 'TOBUD072' exhibits conical flower spikes with white flowers.
3. *Buddleja* 'TOBUD072' exhibits a long flowering season.

The closest comparison cultivar is *Buddleja* 'Tobudviolet' (not patented). 'TOBUD072' is distinguishable from 'Tobudviolet' by the following characteristics:

1. 'TOBUD072' has white flowers. The flowers of 'Tobudviolet' are violet.
- 'TOBUD072' is distinguishable from the female parent 'BU05017' by the following characteristics:
  1. 'TOBUD072' has longer flower spikes.
  2. 'TOBUD072' exhibits a more compact habit.
  3. 'TOBUD072' exhibits a larger number of flowers.

2

BRIEF DESCRIPTION OF THE DRAWING

The accompanying photograph illustrates the distinguishing traits of *Buddleja* 'TOBUD072'. The plant in the photograph shows a view of the inflorescence on a 4 month old plant. The photograph was taken using conventional techniques and although colors may appear different from actual colors due to light reflectance it is as accurate as possible by conventional photographic techniques.

BOTANICAL DESCRIPTION OF THE PLANT

The following is a detailed description of the new *Buddleja* cultivar named 'TOBUD072'. Data was collected in Mainz, 15 Germany from 4 month plants grown outdoors in 16 cm. diameter containers. The time of year was Fall and the average temperature was 20 degrees Centigrade during the day and 10 degrees Centigrade at night. The light level was natural light. No photoperiodic treatments or growth retardants were used. Color determinations are in accordance with The Royal Horticultural Society Colour Chart 2007 edition, except where general color terms of ordinary dictionary significance are used. The growing requirements are similar to the species. 20 'TOBUD072' has not been tested under all possible conditions and phenotypic differences may be observed with variations in environmental, climatic, and cultural conditions, however, without any variance in genotype.

Botanical classification: *Buddleja davidii* 'TOBUD072'.

30 Annual or perennial: Perennial.

Parentage: 'TOBUD072' is the product of the female or seed parent a proprietary *Buddleja davidii* identified as 'BU05017' and an unknown male or pollen parent.

Plant type: Woody shrub.

35 Vigor: Strong.

Growth habit: Upright.

Plant shape: Bushy, upright.

Suitable container size: 16 cm. pots.

Height: 50 to 70 cm. in height.

Width: 40 to 50 cm. in width.

40 Low temperature tolerance: -20° Centigrade.

High temperature tolerance: 45° Centigrade.

Propagation: Cuttings or tissue culture.

Time to initiate roots in summer: 14 days to initiate roots at 22° Centigrade.		Flower aspect.—Outward.
Time to initiate roots in winter: 20 days to initiate roots at 20° Centigrade.		Flower shape.—Salverform.
Time to produce a rooted cutting or liner in summer: 21 days at 22° Centigrade.	5	Flower dimensions.—8.5 mm. in diameter and 10 mm. in height.
Time to produce a rooted cutting or liner in winter: 28 days at 20° Centigrade.		Throat color.—23A.
Crop time: Approximately 3 months.	10	Tube length.—10 mm.
Root system: Fine and fibrous.		Tube diameter.—1 mm.
Stem:		Tube color.—23D.
<i>Basal branching</i> .—Yes.		Flower longevity.—5 to 8 days.
<i>Average number of lateral branches</i> .—12.		Number of petals.—4.
<i>Pinching</i> .—Yes.		Fused or unfused.—Fused.
<i>Lateral branch diameter</i> .—3 to 4 mm. in diameter.	15	Petal arrangement.—Cruciform.
<i>Lateral branch length</i> .—40 cm. in length.		Petal texture.—Smooth both sides.
<i>Internode length</i> .—4 cm.		Petal shape.—Reniform.
<i>Stem shape</i> .—Round.		Petal margin.—Undulate.
<i>Stem strength</i> .—Strong.	20	Petal apex.—Obtuse.
<i>Stem color</i> .—193A and 199A.		Petal base.—Fused with corolla.
<i>Pubescence</i> .—Present.		Petal length.—4 mm.
Foliation:		Petal width.—3 mm.
<i>Leaf arrangement</i> .—Opposite.		Petal color when opening (upper side).—N155B.
<i>Compound or single</i> .—Single.		Petal color when opening (under side).—N155B.
<i>Number of leaves per lateral branch</i> .—20 to 26.		Petal color fully opened (upper side).—N155A.
<i>Leaf shape</i> .—Lanceolate.		Petal color fully opened (under side).—N155B.
<i>Leaf apex</i> .—Acute.		Petal color fading to.—N155A.
<i>Leaf base</i> .—Acuminate.		Self-cleaning or persistent.—Persistent.
<i>Leaf length</i> .—8 to 9 cm. in length.	30	Sepals:
<i>Leaf width</i> .—2.5 to 2.8 cm. in width.		<i>Sepal arrangement</i> .—Cruciform, clasping.
<i>Texture</i> .—Glabrous both surfaces.		<i>Number of sepals</i> .—4.
<i>Pubescence</i> .—Young leaves covered with short hairs on both sides.		<i>Sepal shape</i> .—Ovate.
<i>Leaf margin</i> .—Serrate.	35	<i>Sepal margin</i> .—Entire.
<i>Venation pattern</i> .—Anastomosing.		<i>Sepal apex</i> .—Obtuse.
<i>Young leaf color (upper surface)</i> .—137A.		<i>Sepal base</i> .—Fused.
<i>Young leaf color (lower surface)</i> .—191A.		<i>Sepal dimensions</i> .—3.0 mm. in length and 2.0 mm. in width.
<i>Mature leaf color (upper surface)</i> .—137A.		<i>Young sepal color (upper side)</i> .—N137B.
<i>Mature leaf color (lower surface)</i> .—191A.		<i>Young sepal color (under side)</i> .—N137B.
<i>Vein color (upper surface)</i> .—191D.		<i>Mature sepal color (upper side)</i> .—N137B.
<i>Vein color (under surface)</i> .—191D.		<i>Mature sepal color (under side)</i> .—N137B.
<i>Leaf attachment</i> .—Petiolate.	40	Calyx:
<i>Petiole dimensions</i> .—3 mm. in length, and 1.5 mm. in diameter.		<i>Calyx shape</i> .—Lyriform.
<i>Petiole color</i> .—191D.	45	<i>Calyx dimensions</i> .—2 mm. in length and 1 mm. in diameter.
<i>Durability of foliage to stress</i> .—Strong.		Peduncle:
Flower:		<i>Peduncle dimensions</i> .—3 mm. in length and 2 mm. in diameter.
<i>Inflorescence arrangement</i> .—Terminal and lateral verticillasters.	50	<i>Peduncle angle</i> .—20 degrees from stem.
<i>Inflorescence dimensions</i> .—7 to 10 cm. in length and 4 cm. in width.		<i>Peduncle strength</i> .—Moderate.
<i>Quantity of flowers per inflorescence</i> .—200 to 250.		<i>Peduncle color</i> .—192A.
<i>Flower type</i> .—Salverform.		Pedicels:
<i>Quantity of flowers per lateral stem</i> .—3 to 5 spikes.	55	<i>Pedicel length</i> .—2 mm.
<i>Quantity of flower buds per lateral stem</i> .—3 to 5 spikes.		<i>Pedicel diameter</i> .—1 mm.
<i>Quantity of flowers and buds per plant</i> .—4000 to 6250.		<i>Pedicel color</i> .—138D.
<i>Natural flowering season</i> .—June to October.		Reproduction organs:
<i>Time to flower</i> .—6 weeks.		<i>Stamen number</i> .—4.
<i>Rate of flower opening</i> .—Every 3 to 4 days.	60	<i>Filament length</i> .—4 mm.
<i>Fragrance</i> .—Strong.		<i>Filament color</i> .—23A.
<i>Flower bud length</i> .—10 mm.		<i>Anther shape</i> .—Ovate.
<i>Flower bud diameter</i> .—2 mm.		<i>Anther length</i> .—1.0 mm.
<i>Flower bud shape</i> .—Clavate.		<i>Anther diameter</i> .—0.5 mm.
<i>Bud color</i> .—N155C.	65	<i>Anther color</i> .—11D.
<i>Rate of bud opening</i> .—3 to 4 days.		<i>Amount of pollen</i> .—Low.

Style color.—192D.

Ovary color.—192D.

Fruit and seed production has not been observed.

Disease and pest resistance: Disease and pest resistance has not been observed.

5

The invention claimed is:

1. A new and distinct variety of *Buddleja* plant named 'TOBUD072' as described and illustrated.
